BY *Jacques R. N. Patte*

UNITED STATES PATENT OFFICE

2,377,947

VALVE FOR FIRE PROTECTIVE SYSTEMS

Leroy M. Lewis, Rosemont, Pa.

Application February 20, 1943, Serial No. 476,515

2 Claims. (Cl. 251—10)

This invention has to do with fire protective systems, and is concerned primarily with a so-called "flood" or "deluge" valve which is included as the main control of dry pipe systems.

A flood or deluge valve of the type with which this invention is concerned is illustrated and described in the patent to Rowley, No. 1,947,309, and also in the patent to Lewis, No. 2,342,589.

Each of these valves is characterized as including a main clapper which is pivotally mounted within the valve casing, and normally held in closed or sealing position by a latch. Cooperating with this clapper is a valve seat ring and a diaphragm having an inner lip which overhangs the inner periphery of this seat ring. This annular diaphragm is ordinarily held in position on the valve seat ring by a screw-retaining member and when the clapper is closed, it is urged against the clapper by the pressure of fluid from the source of supply and thus establishes the sealing relation.

An arrangement of clapper, valve seat ring, and annular diaphragm such as is typified by either of the above identified patents, presents certain disadvantages which are intended to be obviated by this invention. This annular diaphragm encircles the main passage through which all the water going to the dry pipe system must pass. Due to the overhanging of the diaphragm, the cross-sectional area of the passage is restricted and the flow of water to the system for fire extinguishing purposes is materially impeded.

Ordinarily, these dry pipe systems are tested at periodic intervals, and the test, of course, involves a flow of water through the deluge valve. Every time the water so flows, the diaphragm is flexed because of the overhanging relation, and the ultimate result is that this continuous or repeated flexing shortens the effective life of the diaphragm.

Another important disadvantage with the now-known arrangement is that it is necessary that the diaphragm be firmly clamped in position on the valve seat ring. In order to establish this firmly clamped relation, the retaining ring must be screwed down tight, and, during the last few turns, the flange of the retaining ring which engages the diaphragm causes distortion or rupturing which results in appreciable damage and shortens the life of the diaphragm.

With all of these undesirable factors in mind, this invention has in view as its foremost objective, the provision of a flood or deluge valve of the type above noted, including a novel arrange-

ment of clapper, valve seat ring, and sealing diaphragm. More in detail, the invention has in mind the provision of such an assembly in which any overhanging or restriction of the passage by the diaphragm is entirely eliminated.

In attaining this end, the diaphragm is carried by the clapper rather than the valve seat ring, and provision is made for utilizing the pressure of the water in the main passage to urge the diaphragm into effective sealing position.

Yet another object of the invention is the provision, in a valve of the type aforesaid, of a clapper valve seat ring and diaphragm assembly in which the clapper and valve seat ring are formed with complementary meeting grooves between which the diaphragm is positioned. Small ducts or passageways communicate from back of the groove in the clapper to the main passage in the valve, so as to conduct the pressure fluid in the valve passage to the annular groove in the clapper and thus force the diaphragm into the groove in the seat ring and establish an effective seal.

Various other more detailed objects and advantages of the invention, such as arise in carrying out the above noted thoughts in a practical embodiment will in part become apparent, and in part be hereinafter stated as the description of the invention proceeds.

The invention therefore comprises a flood or deluge valve including a valve seat ring that is mounted in the main valve passage and which is formed on its valve seat surface with an annular groove. A pivotally mounted clapper is formed with a groove complementary to the groove in the valve seat ring, and substantially opposite thereto. The clapper is also formed with ducts which communicate between the groove therein and the main valve passage. A flexible diaphragm is mounted on the clapper in a position in which it is interposed between the clapper and the valve seat ring. Pressure of fluid in the main valve passage is transmitted through the ducts to the annular groove in the clapper where it forces the diaphragm into the groove in the seat ring to establish an effective seal.

For a full and more complete understanding of the invention, references may be had to the following description and accompanying drawing, wherein:

50 Figure 1 is a vertical section through a deluge valve including a clapper, seat ring, and diaphragm assembly designed in accordance with the precepts of this invention.

Referring now to the drawing wherein like reference characters denote corresponding parts,

the casing of a deluge valve is identified by the reference character C. This casing includes a main valve passage 10 which communicates with the source of supply of water which is maintained under a required pressure. At the location where the passage 10 communicates with the interior of the casing C, the passage 10 is slightly restricted to provide a threaded neck 11. Mounted in this threaded neck 11 is a valve seat ring which is referred to in its entirety by the reference character R. This ring R comprises a main stem 12 which is exteriorly threaded and screwed into the neck 11. The main stem 12 terminates at an abutment shoulder which takes the form of an external annular flange 13, that abuts the upper end of the threaded neck 11. The valve seat ring R also includes an upper ring-like portion 14 having a seat face formed with an annular groove 15.

A clapper is identified by the reference character 16, and is shown as being pivotally mounted at 22 within the casing C. Latch mechanism, referred to in its entirety by the reference character L, is shown as mounted within the casing C and cooperates with the clapper 16 to maintain the latter in closed or sealing position.

The clapper 16 has an annular ring-like flat face 17 that is arranged substantially opposite and slightly spaced from the valve seat face of the ring R, when the clapper is in closed position. The face 17 is formed with an annular groove 18 which is complementary to and substantially opposite the groove 15. Ducts shown at 19 establish communication between the groove 18 and the passage 10.

An annular diaphragm of ring-like formation is shown at 20 as mounted on the face 17 of the clapper 16 by a clamping or retaining ring 21. This diaphragm 20 may be made of rubber or any suitable rubber composition having required properties of flexibility, etc. It will be noted that the inner periphery of the diaphragm 20 substantially aligns with the inner periphery of the face 17 and the bore through the valve seat ring R. Thus, there is no overhang on the part of the diaphragm.

While the operation of the above described clapper, valve seat ring, and diaphragm assembly is believed to be obvious, it may be briefly outlined by noting that, with the clapper 16 in the closed position illustrated, fluid under pressure passes from the main passage 10 through the ducts 19 to the annular groove 18 whence it engages the diaphragm 20 and forces a portion of the latter into the annular groove 15. Thus an effective seal is established.

When the clapper is opened, due to release of the latch L by a mechanism such as that shown in either of the above identified patents, the diaphragm is removed completely from the passage 10, and cannot possibly be deleteriously affected by the rush of water through the passage 10 to the dry pipe system. It is further noted

that there is no flexing of the diaphragm as an incident to operation of the valve, nor is there anything in the manner in which the diaphragm is mounted which would tend to distort, rupture, or weaken the same.

It is evident that the force of the clapper 16, which is rendered effective by the latch L, is effective to urge the diaphragm 20 against the face of the valve seat ring R. The force of pressure fluid in the passage 10 is also rendered effective, through the medium of the ducts 19 and groove 18, to urge the diaphragm 20 in the same direction. Thus, there is no condition where one portion of the diaphragm is urged in one direction by the clapper and in the opposite direction by the pressure fluid, as is the case in either of the above identified patents. The forces of the clapper and pressure fluid are localized and concentrated in the same area and are effective in the same direction.

While a preferred specific embodiment of the invention is hereinbefore set forth, it is to be clearly understood that the invention is not to be limited to the exact constructions illustrated and described, because various modifications of these details may be provided in putting the invention into practice, within the purview of the appended claims.

What is claimed is:

1. In a deluge valve of the character described, a valve casing having an inlet and an outlet, an assembly comprising a valve seat ring mounted in said inlet and having a valve seat face formed with an annular groove; a pivotally mounted clapper having a face arranged substantially parallel to said valve seat face when the clapper is in closed position, said clapper face being formed with an annular groove that is complementary to and opposite to said groove in said valve seat ring; the clapper also being formed with ducts communicating between said groove in the clapper face and said inlet; and a sealing diaphragm carried by said clapper on said clapper face and having a portion positioned between said grooves whereby fluid under pressure from said inlet is rendered effective through said ducts and clapper groove to force said flexible diaphragm into said groove in the valve seat ring.

2. In a deluge valve including a valve casing having an inlet and an outlet, an assembly comprising a valve seat ring in said inlet and having a valve seat face formed with an annular groove; a clapper having a face formed with an annular groove; a sealing diaphragm interposed between said clapper and said valve seat face; and pressure fluid means communicating between said inlet and said groove in the clapper for forcing said diaphragm into said groove in said seat ring, said pressure fluid means including ducts communicating between the other of said grooves and said valve passage.
